UNITED STATES PATENT OFFICE.

MORITZ WEISS, OF NEW YORK, N. Y.

EMERGENCY LOCK FOR DOORS.

Application filed February 25, 1926. Serial No. 90,449.

The invention relates to locking devices for doors, more especially to an emergency lock which may be controlled from some distant point (more or less concealed) when 5 it is desired to lock a door as, for example, in an emergency such as a "hold up"; or as for shut-out purposes, it being understood that the emergency lock is to be installed in addition to the usual lock associated with a door.

The invention has for its object a lock of this character which, while permitting the door to be opened only by its special key, after the lock has once been sprung, 15 is so constructed and arranged that continued operation of the actuating means for setting the lock will not serve to release the same, at least not without simultaneous operation of an additional member which becomes accessible only when the door has again been opened. Unauthorized opening 20 of the door is thus not possible, and without a proper key therefor the door will remain in its locked condition. The invention, furthermore, contemplates a lock which during 25 normal conditions will permit the door to function in the usual manner, the emergency control of said lock being applied electrically and is possible from various 30 points which, under the circumstances, would be located for inconspicuous operation. Provision is made, also, whereby a door thus controlled may be maintained open, as during the warmer seasons of the 35 year, the same being further equipped then with mechanism for releasing the door to effect its closing simultaneously with the emergency operation of the lock.

The nature of the invention, however, will 40 best be understood when described in connection with the accompanying drawings, in which—

Fig. 1 is a fragmentary front elevation of the novel lock device installed in the 45 casing or frame for a door.

Fig. 2 is a fragmentary elevation of a door and frame therefor, the latter being broken away to disclose the location therein 50 of the novel locking device, while the frame plate or cover of said locking device is removed to expose the interior thereof.

Fig. 3 is a horizontal section thru the lock and portion of the frame and door, taken 55 on the line 3—3, Fig. 2, looking in the direction of the arrows, the position shown in dotted lines indicating the position of the

keeper member when the lock has been sprung.

Fig. 4 is a rear elevation of the lock as mounted in the door frame.

Fig. 5 is a horizontal section thru the lock taken on the line 5—5, Fig. 4, and looking in the direction of the arrows.

Fig. 6 is a detail fragmentary view of the locking bar and associated detent member.

Fig. 7 is a diagrammatic view illustrating the general arrangement of installation of the novel lock.

Referring to the drawings, 10 designates a suitable casing or frame of a door 11 which latter is mounted to swing, generally under spring pressure, as by the action of spring hinges 11', to insure its closing in manner well understood. The door is equipped also with any of the usual types of lock 12 for 70 normally securing said door, it being understood that the novel and emergency lock is in addition to such lock 12. To this end, the emergency lock 13 is to be mounted within the door and frame and comprises locking 75 mechanism which is set for example within said frame, as indicated in Figs. 1 and 2, and which has a front strike or keeper plate 14 provided with a recess or cavity 15 cut away at one side. In said recess is pivotally 80 mounted the keeper member, the same comprising two portions, both of which rock in the lock casing and the outer and latch engaging portion 16 being yieldable in one direction against the action of a coil spring 85 17, while its oscillatable movement in the other direction is limited by a stop arm 18 or lateral extension of a locking bar 19 in manner hereinafter set forth. A mortise 90 lock 20 of the latch bolt type, or double cylinder latch lock, with latch 21 is mounted in the door; and, normally, the said keeper portion 16 maintains a position well within the recess 15 so that the latch 21 will clear 95 same and may ride freely thru the recess in manner well understood. However, when the lock is set for an emergency, the keeper 16 is brought forward substantially flush or slightly beneath the face of the keeper plate, as indicated in dotted lines, Fig. 3, so as to 100 provide a rigid abutment which the said latch cannot pass, release of the same therefrom being effected only by the use of the proper key inserted in the key hole 22 in manner well understood. The arrangement 105 is such, furthermore, that after having once been set to the locking position, the same

110

cannot be restored to its normal inoperative position until the door itself has first been opened and a rod 23 extending outwardly thru the keeper plate with its outer end 5 lying flush with the surface thereof is pushed inwardly and simultaneously therewith electrical control means, hereinafter described, caused to be operated.

Actuation of the emergency lock is effected thru the energization of an electro-magnet 25 which causes its pivoted armature 26 to be attracted thereto, it being understood that the closing of the circuit to this electro-magnet may be effected by one or more circuit closing means 27 and 27' located at one or more suitable positions more or less remote and under the control of properly authorized parties. As shown in Fig. 7, one of the circuit closers as the double-pole switch 27 is located at a distant point and another as the single-pole switch 27' is placed on the door frame so as to be convenient when the emergency lock is to be reset. The said armature is designed to impart an inward movement 20 to the reciprocable locking bar 19 as thru a lateral extension 28 engaging an upwardly directed arm 29 lying in the path of movement of said extension 28. The locking bar 19, normally, is urged outwardly toward the keeper plate by a coil spring 30 pressing against its inner end 31 which is mounted to slide in a wall 32 of the casing. Bar 19 is further guided by means of the lateral extension 18 which rides between two rollers 34 25 carried by a bracket 35 attached to the lock casing; and the same extension is notched at 36 for the purpose hereinafter set forth.

A further arm 40 extends upwardly from the bar 19 and is notched as at 41 at its lower end and tapers along its one side toward said notch. Carried by the inner member 42 of the rocking keeper members is a pin or triangular detent 43 which extends laterally from an arm 43' thereof over the bar 19 and is designed to lock in the notch 41 of said arm 40 to retain the outer portion 16 of the keeper in its retracted position. So soon, however, as the bar 19 is moved inwardly, as by energizing the electro-magnet and causing the extension 28 to engage the arm 29 of the said bar, the detent 43 is released and permits the rocking arm 42 of the member to fly upwardly due to the spring pressure transmitted thereto thru its contact with member 16. To this end, the rounded inner end of member 16 is adapted to ride in a cavity or groove 44 when said member 16 is released thru disengagement of a pin 45 thereof from contact with the extension 18 of bar 19, the said pin passing thru the notch 36 in said extension under inward movement of the latter thru the action of armature 26 and simultaneously with the freeing of the detent 43. The movement of member 42 is arrested by a stop 46 directed

toward the bar 19 from a wall of the casing and engaging its arm 43', the detent 43 then assuming a position immediately over the top of the arm 40 upon which it rests. Furthermore, the outer end of arm 43' rests 70 upon the extension 28, the notch 47 in said arm having permitted the said arm to clear said extension while the armature was attracted to its magnet.

Keeper 16 is thus set to block the passage 75 of latch 21 out of the recess 15; and the inward movement of bar 19 as would result thru subsequent actuation of the electro-magnet will not suffice to free the detent from its engagement with the top of arm 40 for 80 the pole pieces of said electro-magnet prevent sufficient throw of its armature to move bar 19 the required distance to clear the said detent. There is, furthermore, no actuating force tending to return the detent to a position for effecting subsequent setting position, this being effected generally by manually pressing the member 16. The restoration of the detent to its setting position for 85 subsequent locking can be effected only by positively pressing inwardly the bar as in exerting pressure upon its outer and reduced end 23 which extends to the outer face of the strike plate thru a bushing 48 90 thereof, which bushing may serve as a bearing for the same and also to facilitate assembly as well as preventing bar 19 from going thru the casing wall. This outer end will not be accessible, however, until the door has 95 been opened thru withdrawal of the latch 21 by inserting the proper key at 22. However, the keeper 16 will still not be freed thereby for the arm 43' of the other keeper portion 42 still rests upon the lateral extension 28 of the armature and is freed therefrom 100 only when the armature is attracted to move inwardly the lateral extension as hereinbefore set forth. Portion 42 and arm 43' may then be forced downwardly manually by 105 pressing upon the outer and cooperating member 16, carrying the detent with it, the same moving along the tapered side of the upright or arm 40 and finally slipping into its notch 41 as inward pressure is removed from the outer end 23 of the said bar. This 110 restores the lock to its normal non-locking condition. It will be appreciated that in the locking position, the rocking arm 42 is supported at two points, viz: the arm 40 and extension 28, and that considerable resistance 115 is thus provided against attempts to force the lock.

If it be desired to maintain the door open, as during the warmer seasons of the year, a catch 50 may be provided on the floor to engage the bottom of the said door thru an electrically released locking means 51 of well-known construction and which may be associated therewith so that the door may be closed under the action of a switch 52 from 120

a distance, also simultaneously with the operation of the emergency lock. This may be effected by the double-pole switch 27 which not only closes the circuit to the said releasing means 51 but also the circuit for energizing the electro-magnet 25. When it is desired to operate only the releasing means 51, the switch 52 is provided conveniently to the door so that the latter may be closed and locked in the normal manner—it being understood that use is made of the emergency lock only in emergencies and its presence is not to be a matter of general knowledge, and likewise the operating switches are to be within the control of the proper authorities.

I claim:—

1. The combination with a door and a door frame; of a locking mechanism mounted within the latter, and a latch mounted in the door for engagement with the locking mechanism; electrical means for operating the locking mechanism to prevent withdrawal therefrom of the latch; and mechanical means adapted for manual operation to cooperate in the resetting of the locking mechanism and accessible only after the door has been opened.

2. The combination with a door and a door frame; of a locking mechanism mounted within the latter and including a keeper and keeper plate; a latch mounted in the door for engagement with the said keeper; electrical means for operating the locking mechanism to prevent withdrawal therefrom of the latch; and means extending from the locking mechanism outwardly thru the keeper plate to cooperate in the resetting of said locking mechanism.

3. The combination with a door and a door frame; of a locking mechanism mounted within the latter and including a keeper and keeper plate; a latch mounted in the door for engagement with the said keeper; electrical means for operating the locking mechanism to prevent withdrawal therefrom of the latch; and a locking bar of the locking mechanism adapted to be actuated by the said electrical means and having an extension projecting thru the keeper plate whereby said locking bar may be mechanically moved beyond the distance possible by the electrical means.

4. The combination with a door and a door frame; of a locking mechanism mounted within the latter and including a keeper and keeper plate; a latch mounted in the door for engagement with the said keeper; electrical means for operating the locking mechanism to prevent withdrawal therefrom of the latch; and a locking bar of the locking mechanism spring urged outwardly and adapted to be actuated by the said electrical means and having an extension projecting thru the keeper plate whereby said locking

bar may be mechanically moved in opposition to said spring and beyond the distance possible by the electrical means.

5. The combination with a door and a door frame; of a locking mechanism mounted within the latter and including an outer and an inner rocking keeper member, and a detent carried by the inner of said members; a latch mounted in the door for engagement with the outer of the keeper members, electrical means for controlling the position of the detent; and a locking bar of the locking mechanism adapted to be actuated by the said electrical means and for manual actuation.

6. The combination with a door and a door frame; of a locking mechanism mounted within the latter and including a keeper plate, an outer and an inner rocking keeper member, and a detent carried by the inner of said members; a latch mounted in the door for engagement with the outer of the keeper members; electrical means for controlling the position of the detent; and a locking bar of the locking mechanism adapted to be actuated by the said electrical means and having an extension projecting thru the keeper plate whereby said locking bar may be mechanically moved beyond the distance possible by the electrical means.

7. An emergency lock device comprising a casing adapted for mounting in the frame of a door, the latter provided with a spring latch and the former having a keeper plate with recess therein, said plate being fitted substantially flush with the face of the door frame, a pivoted and spring urged keeper member comprising two cooperating rocking portions, the one extending into the recess and normally depressed a substantial distance beneath the surface of the keeper plate sufficient to pass the cooperating latch of the door, electrically controlled means to release the keeper and to lock the same in a position within the recess near the surface of said keeper plate, said means including a locking bar slidably mounted in the casing and having a pair of arms projecting at right angles therefrom, one of which is notched at the bottom and tapering thereto from the top, means to guide said bar and a spring to urge the same normally outwardly, said bar having also a rod extending outwardly thru the keeper plate and terminating substantially flush with its outer face and the other projecting arm of the pair being adapted for engagement with the electrically controlled means to be moved thereby in opposition to the said spring urging said bar outwardly, and a rocking stop member for the inner keeper member.

In testimony whereof I affix my signature.

MORITZ WEISS.
